(57) **CLAIM**

The ornamental design for a mailbox indicator flag, as shown and described.

DESCRIPTION

FIG. 1 is a top, rear perspective view of a mailbox indicator flag showing my new design;
FIG. 2 a top plan view thereof;
FIG. 3 is a bottom plan view thereof;
FIG. 4 is a left side elevation view thereof;
FIG. 5 is a right side elevation view thereof;
FIG. 6 is a front elevation view thereof; and,
FIG. 7 is a rear elevation view thereof.

The broken lines shown in the drawings represent portions of the mailbox indicator flag that form no part of the claimed design.
